UNITED STATES PATENT OFFICE.

EARLE F. POTTER, OF CRESTON, IOWA, ASSIGNOR TO THE POTTER SPECIALTIES COMPANY, OF CHICAGO, ILLINOIS, A CORPORATION OF ILLINOIS.

SIGNALING DEVICE.

Application filed November 3, 1920. Serial No. 421,448.

To all whom it may concern:

Be it known that I, EARLE F. POTTER, a citizen of the United States, residing at Creston, in the county of Union and State 5 of Iowa, have invented a certain new and useful Improvement in Signaling Devices, of which the following is a full, clear, concise, and exact description, reference being had to the accompanying drawings, forming 10 a part of this specification.

My invention relates to signaling devices, particularly to those of the so-called "traffic signal" type and is in general an improvement upon my prior invention set out in 15 my application, Serial No. 358,998 filed February 16, 1920.

In my prior invention I have disclosed a signaling device, the indicating surfaces of which are in the nature of a pair of dis- 20 tinктивely colored helical discs or plates one of which is adapted to be threaded through the other into position forward or to the rear of the same according to the signal or indication to be given. One signal having 25 two distinct indications is mounted upon each side of the vehicle as upon the fender or in some other prominent position. Like surfaces of a suitable color such as white, for example, normally in indicating position 30 in each device indicate that the vehicle is to continue in its straight ahead movement. An intended turn to the right is indicated by operating the signal on the right hand side of the vehicle to position 35 the normally concealed indicating surface which is of some different distinctive color such as red or green forward of the disc or surface normally in indicating position. The signal on the left hand side is operated 40 to indicate an intended turn to the left. An intended stop or diminution in speed is indicated by operating both signals simultaneously to position the normally concealed indicating surfaces forward of the surfaces 45 normally in indicated position. By providing two pairs of cooperating indicating discs in each housing the driver's intention is conveyed to the front as well as to the rear of the vehicle.

50 The novel manner of concealing one sur-

face behind or positioning it forward of the other according to the signal or indication to be given makes for a simple, compact and attractive device which may be inexpensively manufactured and easily assembled and is 55 effective and positive in operation. The large indicating surface relative the dimensions of the entire device is another important feature had by this arrangement. The area required for the two positions of 60 each of the two indicating surfaces of the device is substantially the same as that required for either of such surfaces in one position, that is, there are no laterally offset casing portions or the like for receiving the concealed indicating surface as heretofore.

My present invention seeks a still more highly refined device of still more efficient, 65 positive and reliable operation, and still further compactness and simplicity in an improved assembly.

A still further aim of my present invention is the provision of a device which will require very little attention from the operator.

Certain features of my present invention are:

(a) An improved means for quickly and positively operating the device to position 80 the desired signaling surface or surfaces in indicating position,

(b) Interlocking means for positively locking the indicating surface or surfaces against displacement from their adjusted or 85 set position,

(c) An improved switch for energizing the signal operating means independently or simultaneously as desired when two signals are employed.

(d) Means for automatically terminating the period of energization of the signal operating means upon positioning the desired signaling surface in indicating position, thereby precluding the possibility of 95 leaving the circuit closed after the particular surface is positioned for the desired indication.

Certain arrangements and details of construction which are novel and important and 100

are made the subject matter of some of the appended claims together with other features of the invention not hereinbefore set forth will appear from the following detailed description and the claims taken with an inspection of the accompanying drawings, in which:

Figure 1 is a vertical longitudinal sectional view through a signaling device embodying my present invention;

Figure 2 is a vertical sectional view taken substantially on the line 2—2 of Figure 1 showing the wiring connections of the device more or less diagrammatically;

Figure 3 is an isometric view of one pair of cooperating indicating surfaces of the device;

Figure 4 is a rear elevational view of an automobile showing one arrangement of the signaling devices of my present invention in connection therewith;

Figure 5 is an axial section of the controlling switch taken substantially on the line 5—5 of Figure 6;

Figure 6 is a plan view of the controlling switch taken substantially on the line 6—6 of Figure 5;

Figure 7 is a horizontal sectional view taken substantially on the line 7—7 of Figure 5 showing diagrammatically the wiring connections to the signaling devices;

Figure 8 is a side elevational view of the terminal blocks taken from the right in Figure 7;

Figure 9 shows diagrammatically an alternative interlocking arrangement; and

Figures 10 and 11 are diagrammatic views of still further modifications.

As stated before one of signaling devices of my invention is mounted in some prominent position on each side of the vehicle as for example as shown at 1 and 2 upon the rear fenders 3 and 4, respectively, of the vehicle 5 shown in Figure 4. The mounting brackets of the signals in this particular instance would be of a different formation than the bracket shown in connection with Figure 2 which bracket is illustrative of a type that may be used for mounting the signals upon the sides of the vehicle body or even upon the windshield under certain conditions. If arranged as in Figure 4 the signals may even be built in as permanent equipment in much the same manner as the head lights of certain of the better class cars are now built. However, the particular mounting of the signals is really immaterial in so far as my present invention is concerned.

Each of the signals 1 and 2 which are substantially identical so that a detailed description of one will suffice for both comprises a frame including a pair of substantially vertical frame members 6 and 7 (Figure 1) between which the horizontally

extending portion of a frame member 8 is secured as by means of suitable machine or set screws or the like as shown, although of course the frame member 8 may be formed integral with the frame members 6 and 7 if so desired. The opposite ends of the frame member 8 project up at substantially right angles to the horizontally extending portion thereof and are provided with horizontally aligned openings through which openings a tube 9 extends. The opposite ends of the tube 9 are securely mounted in blocks 10 and 11, respectively, which blocks extend longitudinally between the stationary signaling discs or surfaces 12 and 13 of the device and serve to maintain the proper spaced relation of such surfaces at substantially diametrically opposite points in a horizontal plane. The peripheries of the discs or plates 12 and 13 are secured to the blocks 10 and 11 at these points by means of suitable machine or set screws 14 or the like (Figures 2 and 3). The peripheries of the discs 12 and 13 are secured by means of suitable screws at substantially opposite vertical points to the opposite end of the vertical frame members 6 and 7, respectively, of the device as clearly shown in Figure 2.

The relatively stationary signaling surfaces 12 and 13 are in the nature of substantially continuous helical plates or discs slotted as shown at 15 in Figure 3 and inclined uniformly from one edge 16 of the slot to the other edge 17. The upper and lower edges of the frame members 6 and 7 to which the surfaces 12 and 13 are attached are provided with mounting shoulders, the upper shoulder of the member 7 projecting beyond the lower shoulder thereof while the lower shoulder of the frame member 6 projects beyond the upper shoulder of said member. The ends of the blocks 10 and 11 to which the signaling surfaces are attached project accordingly so as to accommodate the helical formation of the stationary signaling surfaces, all points of which surfaces are thereby maintained substantially equi-distant apart.

The rotatable signaling surfaces or indicating discs 18 and 19 are secured as by means of suitable machine screws 20 upon the opposite ends of a shaft 21 which shaft extends through and is supported adjacent its opposite ends in the frame members 6 and 7. These rotatable signaling discs are, like the stationary discs 12 and 13, in the nature of substantially continuous helical plates slotted as shown at 22 in Figure 3 and inclined uniformly from one edge 23 of the slot to the other edge 24. Like the stationary discs 12 and 13 all points of the rotatable discs 18 and 19 are substantially equi-distant apart and consequently the entire surface of the disc 18 is at all times substantially equi-

- distant from the surface of the disc 12, while the entire surface of the disc 19 is at all times substantially equi-distant from the surface of the disc 13.
- 5 Upon rotation of the shaft 21 the discs 18 and 19 are threaded from one side to the other of the surfaces 12 and 13, respectively, as will be hereinafter more fully set forth.
- 10 A series of annular ridges milled or otherwise formed longitudinally about the periphery of the shaft 21 between the opposite ends thereof provide a series of teeth 26 about the periphery of this shaft, which teeth 26 mesh with a series of cooperating teeth 27 provided annularly about a shaft 28 intermediate the opposite ends thereof. A rack and pinion engagement is thereby effected between the shafts 28 and 21 for converting the rectilinear movement of the shaft 28 into circular movement or rotation of the shaft 21.
- 15 Engagement between the teeth 26 of the shaft 21 and the cooperating teeth 27 of the shaft 28 which shaft 28 is mounted for rectilinear movement within the tube 9 is had by cutting away a portion of the under surface of the tube 9 as shown at 29 in Figure 2. The shaft 28 constitutes the core or plunger of a pair of solenoid windings 30 and 31 wound about the tube 9 between the block 10 and one of the upwardly projecting portions of the frame member 8 and the block 11 and the other upwardly projecting portion of this frame member. Energization of the winding 31 moves the shaft 28 to the right (Figure 2) through the tube 9, rotating the shaft 21 in a clockwise direction to position the disc 18 behind the surface 12 and the disc 19 forward or in front of the surface 13, while energization of the winding 30 moves the core 28 to the left and consequently rotates the shaft 21 in a counter clockwise direction to position the disc 18 in front of the surface 12 and the disc 19 behind the surface 13. Rectilinear movement of the shaft 28 is limited by means of plugs 47 and 48 threaded into the opposite ends of the tube 9 and provided with suitable cooperating lock nuts 49. Obviously movement of the shaft 28 in either direction may be conveniently adjusted by adjustment of either or both of the plugs 47 or 48 as desired.
- 20 Frictional engagement between the cooperating signaling surfaces of the device in threading one surface through the other or at least excessive frictional engagement such as would wear the enamel off these surfaces is effectively prevented by the engagement of a pin or screw 45 threaded through the frame member 7 with a helical groove 46 formed in the shaft 21 at substantially the same pitch as the pitch of the indicating surfaces themselves.
- 25 A plunger 35 reciprocable in a tube 36 mounted at its upper end in the horizontal portion of the frame member 8 is provided with a projecting pin 37 normally projected into engagement with the teeth 26 of the shaft 21 by means of a suitable spring 38 confined between the lower end of the plunger 35 and a plug 39 threaded into the lower end of the tube 36. The shaft 21 is in this manner effectively locked against unintentional rotation from its set or adjusted position such as might otherwise result from the vibration to which the vehicle is subjected. The plunger 35 constitutes the core of a solenoid winding 40 wound about the tube 36. Upon energization of the solenoid winding 30 the winding 40 is in series therewith through a suitable conductor or lead 41. Upon energization of the winding 31 the winding 40 is in series with such winding 31 through a conductor 42. The opposite end of the winding 40 is grounded as shown diagrammatically at 43 in any suitable manner, as for example, to the frame of the device.
- 30 A socket member 50 carrying a suitable lamp 51 is mounted between the upper ends of the vertical frame members 6 and 7 and projects radially through a suitable opening 52 in the annular enclosing frame 53. Within which frame 53 the indicating surfaces and operating mechanism of the device are confined. Interior annular shoulders within the frame member 53 adjacent each of the opposite open faces thereof seat suitable mounting rings 54 and 55 into engagement with which rings the convex-concave exposing panes or lenses 56 and 57 are securely clamped by means of clamping or retaining rings 58 and 59, respectively, which rings are threaded upon the opposite ends of the enclosing frame or band 53. The indicating surfaces, operating mechanism, etc., of the device are securely retained against angular displacement within the enclosing frame 53 by the cooperation of projecting pins 60 carried by the blocks 10 and 11 with suitable longitudinal grooves provided in the interior surface of the frame member 53 as clearly shown in Figure 2.
- 35 Of course, these parts may be otherwise keyed against relative rotation. By providing the grooves in the blocks 10 and 11, for example, and the cooperating pins in the frame member the thickness of the frame member could be decreased.
- 40 A housing 61 encloses the lamp 51 and is provided with signaling panes or targets 62 and 63 securely mounted in suitable frame members 64 and 65. The frame members 64 and 65 with their signaling panes or targets are clamped against the opposite open ends of the housing 61 as by means of a suitable bolt 66 extending through the frame 64 and the housing 61 and threaded

into the opposite frame 65. The targets or panes are preferably made of red or green glass according to the color of the disc or surface for signaling an intended stop or 5 change in course of the vehicle. Turning of the frame members 64 and 65 about the ends of the housing 61 is prevented by the engagement of projecting pins 67 carried by these frame members with suitable 10 operating openings in the ends of the housing 61.

The solenoid winding 30 of the device is energized or supplied through a conductor 68 (Figure 2) which conductor leads up 15 through the hollow mounting bracket 69 and to the terminal strip 70 of the controlling switch as shown diagrammatically in Figure 7. The winding 31 is supplied through a conductor 71 which conductor leads up 20 through the hollow mounting bracket 69 and to the terminal strip 72 of the controlling switch. The lamp 51, one terminal of which lamp is grounded as shown at 73 in Figure 2, is supplied through a conductor 25 74 leading from the other terminal of the lamp socket up through the hollow bracket 69 and thence to the terminal bolt 75 (Figure 7) of the controlling switch.

The controlling switch comprises a casing or housing 76 having a cover or head 77 securely fitted upon the upper open end thereof. A block 78 of insulation mounted within the casing or housing 76 as by means of suitable screws 79 or the like is provided 30 with a boss or hub 80 projecting upwardly through the cover or head 77 and terminating slightly thereabove. The upper end of the boss or head 80 of the insulating block 78 is bored for the reception of a metallic 35 thimble 81 having a flange at its upper end for engaging the upper end of the insulating boss or hub 80. The lower end of the depending sleeve portion of the metallic thimble 81 is bent inwardly or provided 40 with a series of inwardly extending lugs forming a socket in which socket the metallic ball portion 82 of the contact making lever 83 is fulcrumed. The upwardly extending stem of this lever is provided with 45 an insulating finger piece 84, whereby the lever is pivoted about its fulcrum to control the flow of current to the signaling device as will be hereinafter set out. A block of 50 insulation 85 having such openings through its upper surface as will allow for the proper pivotal movements of the lever 83 about its fulcrum is bolted upon the cover or head 77 of the switch, clamping the metallic thimble 81 securely in place. Obviously, with the hub or boss 80 and block 78 55 the thimble 81 is substantially completely enclosed in insulation.

The opposite ends of a terminal strip 86 clamped between the lower or outer surface 60 of the insulating block 78 and an arcuate

block 87 of insulation are bent down along the opposite ends of this block as shown at 88 and 89 in Figures 5 and 7. This terminal strip 86 is connected through a suitable conductor 90 with the terminal bolt 70 75 of the switch. The under surface of the arcuate insulating block 87 carries the terminal strip 72 which terminal strip 72 is connected with the solenoid winding 31 of the signal by way of a conductor or line 75 71 as hereinbefore set out. A downwardly depending arcuate block 91 of substantially less diameter than the diameter of the block 87 is secured to and depends from the block 87 as shown. The terminal strip 70, which terminal strip 70 is connected through the conductor 68 with the solenoid winding 30 of the signal is secured as through suitable screws or the like upon the under surface 80 of the block 91.

Blocks of insulation 92 and 93 together with the block 78 carry terminal strips 94, 95 and 96 connected through suitable conductors 97, 98 and 99, with the lamp and solenoid coils, respectively, of the signaling device mounted upon the opposite side of the car when two of such devices are employed as shown in Figure 4. The adjacent ends of the blocks 87, 91 and 92-93 are spaced sufficiently apart to permit the 95 downwardly extending energizing finger of the lever 83 to be swung about its fulcrum or pivot into engagement with the ends of the terminal strips therebetween. Swinging of the lever 83 at substantially right-angles 100 to the movement between these blocks is permitted by suitable guideways 100 formed in the block 78 and hub or boss 80. The energizing finger of the lever 83 is supplied from a battery 101 or other suitable source 105 by way of a conductor 102 connected to the metallic thimble 81 of the switch. The opposite end of the battery 101 is grounded as shown diagrammatically at 103. The free end of a spring strip 104 carried by the block 78 is bent downwardly and engages the free or inner end of the lever 83 to maintain said lever normally in the position shown in Figures 5 and 8.

The operation of the arrangement thus 115 far described is as follows:

Assume that the rotatable white enameled discs 18 are in indicating position at one of the exposing faces of the signaling devices while the stationary white enameled discs 13 are in indicating position at the other or opposite exposing faces, indicating that the vehicle is to continue in its straight ahead movement. Should the driver intend to turn to the left, the contact making lever 83 is swung about its fulcrum to the left (Figures 5 and 7) through the guideway 100 into engagement first with the bent down end 88 of the terminal strip 86, and finally into engagement with the up-turned 120 125 130

end of the terminal strip 72 against the tension of a spring 105.

Upon engagement between the contact making or energizing finger 83 and the terminal strip 86, the circuit from the source 101, one end of which source is grounded, through the lamp 51 in the left hand signal is completed by way of the conductor 74, causing this lamp to burn. The lever 83 immediately engaging the terminal strip 72 closes the circuit from the source 101 through the solenoid coils 31 and 40 of the left hand signal. Simultaneous energization of the windings 31 and 40 is thereby effected. Energization of the coil 40 releases the shaft 28 while energization of the coil 31 moves the shaft rectilinearly through the tube 9 to the right (Figure 2). This rectilinear movement of the shaft 28 to the right rotates the shaft 21 in a clockwise direction to position the white enameled discs 18 behind the green, red or other distinctively enameled surface 12 and the corresponding green, red or other distinctively enameled discs 19 forward or in front of the white enameled disc surface 13. An effective indication is thereby conveyed to the front and rear when a turn to the left is contemplated. As the lever 83 is released by the operator, contact between the energizing finger thereof and the terminal strip 72 is instantly broken by the spring 105, whereupon the spring pressed locking plunger 35 is forced into engagement with the teeth 27 of the shaft 28 to effectively lock the shaft against unintentional rotation. The period of energization of the coils 30 and 31 is therefore very short.

The lamp, however, continues to burn until the change in course has been made and the lever is moved to the right through the guideway 100 back into its normal position. Upon such movement, contact between the lever 83 and the strip 86 is first broken putting the lamp out of service. Within the remaining movement of the lever 83 back to normal, contact is made with the terminal strip 70 closing the circuit through the solenoid windings 30 and 40 by way of the conductors 68 and 41. The spring arm 150 of the strip 104 is arranged to spring the lever 83 out of engagement with the terminal strip 70 should the lever 83 be unintentionally released when in such position. The shaft 28 is thereupon released and instantly moved to the left to position the white enameled discs 18 in the left hand signal again forward of the green, red or other distinctively enameled surface 12 and the green, red or other distinctively enameled discs 19 again behind the white enameled surface 13.

An intended turn to the right is indicated by swinging the lever 83 about its fulcrum to the right (Figures 5 and 7)

through the guideway 100 to engage the terminal strips 94 and 96 and the strip 95 against the tension of the spring 106 in the same manner as has been fully set out in connection with the left hand signaling device.

Should the driver intend to stop or diminish the speed of the vehicle, the energizing finger of the lever 83 is swung between the adjacent base ends of the blocks 87-91 and 92-93. Upon such movement, simultaneous engagement is first had with the terminal strips 86 and 94 closing the circuits through the lamps in each of the indicating devices. Continuing this movement, simultaneous engagement is finally had with the terminal strips 72 and 95 against the tension of a spring 108, positioning the green, red or other distinctively colored indicating surfaces in indicating position at the front and rear of each of the two signals associated with the machine. Upon returning the lever 83 to its normal position, simultaneous engagement with the terminal strips 70 and 96 again positions the white enameled surfaces in their normal indicating position.

While the surfaces normally in indicating position are preferably enameled white and the surfaces for indicating a change in the course of diminution in speed are preferably enameled green, the particular coloring system used is immaterial in so far as my present invention is concerned. Green is preferably used to avoid possible confusion with the side lights, tail lights, etc., now in use. In this connection, I find that such confusion can be even further avoided by the provision of thermostatic, spring or other suitable means in the lamp circuits for periodically flashing the lamp or lamps when the circuit or circuits as the case may be, therethrough, are closed. Such provisions in connection with my present invention are therefore contemplated in that under certain conditions the effectiveness of the signal is thereby increased.

In Figure 9, I have shown an alternative form of locking means for preventing unintentional movement of the shafts 26 and 28. In this case, the circuit through an electro-magnet 112, which circuit is supplied from a suitable source (not shown) and is grounded as shown at 113 is closed by the left hand end of the shaft 28 as shown in the movement of the shaft to the left upon energization of the coil 30. Current is thereby established through the electro-magnet 112 setting up a magnetic field with ample strength to lock the shaft 28 in this position until the solenoid coil 31 is energized whereupon the shaft 28 is moved to the right to give the proper indication and at the same time closes the circuit through an electro-magnet 110.

grounded at 111, which electro-magnet thereupon effectively locks the shaft against displacement from its right hand position.

In a signaling device for the character 5 of service for which my present invention is particularly adapted, I find that the driver should be relieved of as much attention thereto as possible. To this end, the circuit controlling arrangements shown 10 diagrammatically in Figures 10 and 11 have been provided.

In Figure 10, the contact making lever 115 is supplied from a battery 116 or other suitable source, the opposite end of which 15 battery is grounded at 117. A conductor 118 connects the contact 150 for setting the white indicating surface of one of the signals in its normal indicating position with a suitable spring contact 120 mounted upon an insulating block 121. A conductor 122 connects the contact 150 with a suitable contact mounted upon a similar insulating block in the other signal. Conductors 124 20 connect the terminal strips 125 for setting 25 the green or other distinctively colored surfaces in indicating position, with spring contacts 126 mounted upon the blocks 121 in spaced relation to the contacts 120. Metallic guide blocks 128 secured to the opposite ends of the insulating block 121 form 30 guides along the upper surfaces of which upright posts 129 are adapted for rectilineal movement, these posts being slidably mounted upon the blocks 128 through dove 35 tail or other suitable connections. An insulating strip 130 arranged between and carried by the upright posts 129 carries 40 terminal screws 131 and 132 adapted for making contact with the spring terminals 126 and 120, respectively as will be herein after set out.

The solenoid winding 30" surrounding the shaft 28" is connected with the terminal screw 131 while the winding 31" is connected with the screw 132. A conductor 133 connected into the line 124 between the terminals 125 and 126 leads through a lamp 134 and is grounded as shown at 135.

Assuming that the white indicating surfaces of the signal are in their normal indicating positions and it is desired to signal an intended change in course or stop. The contact making lever 115 is moved into engagement with the desired terminal strip 50 55 60 65 125 setting up a flow of current through the lamp 134 and through the solenoid winding 30" by way of the cooperating contacts 131 and 126, which are in engagement at such time. The solenoid core 28" is thereupon immediately moved rectilinearly to the left. A projection 136 carried by the core or shaft 28" engages the left hand post 129 during such movement and moves the posts 129, insulating strip 130 and terminal screws 131 and 132 to the left along the guide blocks

128. Engagement between the terminal screw 131 and contact 126 is thereby broken opening the circuit through the winding 30" while engagement between the terminal screw 132 and cooperating contact 120 is 70 made. While the coil 30" is thereby de-energized, the lamp 134 will continue to burn so long as engagement between the lever 115 and the terminal strips 125 continues. 75

When the change in course has been made and is desired to return the white surfaces to their normal indicating position, the lever 115 is moved first from engagement with the strip 125 opening the circuit through the lamp and then into its central or normal position in engagement with the contact member 150 closing the circuit through the solenoid winding 31". The resulting movement of the core or shaft 28" to the right 85 automatically opens the circuit through the winding 31" and causes engagement between the screw 131 and the contact member 126 so that this circuit will be automatically set for the succeeding change in course or 90 stop indicating operation. The circuit through the solenoid windings being automatically opened precludes any possibility of unintentionally leaving either of these circuits closed and at the same time, the 95 circuit not energized is automatically set for the succeeding energization thereof. Spring clips 119, 123 and 138 serve to hold the energizing lever 115 in its various 100 adjusted positions. Engagement of the lever 115 with both of the strips 125 simultaneously positions the green, red or other distinctively colored surfaces in each device in indicating position.

In Figure 11 the contact members 151 and 152 are connected as through suitable leads with the contact member 150. With this layout by moving the energizing lever 115 into contact with the contact members 151 and 125' or 152 and 125' an automatic 110 115 120 125 changing from white to red by continuous operation of the signal back and forth from white to red will be obtained in the particular signal energized so long as the energizing lever remains in such contact. In other 115 words, the leads 118' and 124' are tied together at such time and the plunger 28" reciprocates back and forth by the cutting in and out of the automatic switch. The lamp 134' also flashes on and off as the 120 cut-out moves from one position to the other. Such action simultaneously in both signals to indicate a stop is obtained through engagement of the energizing lever with the opposite ends of the contacts 125' and 153 and 154 connected through suitable leads with the contacts 151 and 152.

I do not intend, of course, to be limited to the precise details of construction shown and described.

I claim:

to, a shaft in the tube, a second shaft disposed normal to said first shaft and journaled in said last frame members, said second shaft having teeth projecting through the slot in the tube and engaging with teeth in said first shaft, signal members carried by the opposite ends of said last shaft and cooperating with said first signal members,

and a lug on one of the frame members co-operating with a groove in the signal member carrying shaft for maintaining proper relative positioning of the signal members. 10

In witness whereof, I hereunto subscribe my name this 28th day of October, 1920.

EARLE F. POTTER.
